(57) **CLAIM**

The ornamental design for an aircraft, as shown and described.

DESCRIPTION

FIG. 1 is a front elevational view of an aircraft showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a left, bottom, rear perspective view thereof; and, FIG. 8 is a front, right, top perspective view thereof.

The broken lines in the figures are included for the purpose of illustrating portions of the article which form no part of the claimed design.

1 Claim, 8 Drawing Sheets# US D856,259 S
